FIG. 9

FIGURE 1 is a front exterior perspective view of a vehicle showing my new design;

FIGURE 2 is a rear exterior perspective view;

FIGURE 3 is a fragmentary interior perspective view looking toward the front of the vehicle and taken from the center portion thereof;

FIGURE 4 is a fragmentary interior perspective view looking toward the rear of the vehicle from the driver's compartment;

FIGURE 5 is a fragmentary interior perspective view looking rearwardly and diagonally across toward the left side, the curtains on the window being drawn;

FIGURE 6 is a fragmentary interior perspective view taken opposite FIG. 4, the curtains on the window being drawn;

FIGURE 7 is a fragmentary interior perspective view looking toward the left from the front passenger's seat;

FIGURE 8 is a fragmentary interior perspective view looking toward the right from the driver's seat; and

FIGURE 9 is a fragmentary rear perspective view with the door in open position.

The dominant features of my design reside in the portion illustrated in solid lines.

I claim:

The ornamental design for a vehicle, as shown and described.
